ATTORNEY

UNITED STATES PATENT OFFICE.

DOMENICK SACK, OF VANDERGRIFT HEIGHTS, PENNSYLVANIA.

BOOT OR SHOE UPPER.

939,639.

Specification of Letters Patent.

Patented Nov. 9, 1909.

Application filed February 25, 1909. Serial No. 479,940.

To all whom it may concern:

Be it known that I, DOMENICK SACK, a citizen of the United States, residing at Vandergrift Heights, in the county of Westmoreland and State of Pennsylvania, have invented certain new and useful Improvements in Boot or Shoe Uppers, of which the following is a specification.

My invention relates to an improved blank 10 to be utilized in the formation of the upper portion of boots or shoes of a peculiar style, the leather, or other material used, being stamped out or cut approximately as shown in Figure 2, the entire upper being in one 15 piece, and when properly folded, as herein-after described, will have only two sewed seams, which will be located between the toe and instep.

Another novel feature is the flap or 20 tongue, constituting an integral part of the blank, by means of which a fastening means is provided at or near the heel.

Fig. 1 of the drawing illustrates a completed boot after being shaped and sewed. 25 Fig. 2 shows the blank after being shaped ready for the forming process.

Throughout the several views the letters A, A', A², A³, are the different divisions of the whole or body portion of the blank cut 30 to form the necessary over-lapping and contacting sections. The rear lower flap A³ is first bent forward toward the toe portion A² the dotted line "a—b" representing the rear or heel line of the boot or shoe, the 35 point "c" registering at "d," and the point "e" at "f"; where they are suitably sewed together. The flap A² is next folded down over the edges of the flap A³, the line from "d" to "g" overlapping the line from "c" 40 to "h", thus forming the toe portion. All the sewing that will be necessary is along these aforesaid lines. The rear portion "j" of the upper section A is next brought forward toward the front section A', and the 45 latter portion is left free to be folded backward over the said portion "j", thus completing the formation of the upper. The flap "j" carries a series of buttons or other

fastening means, and the front flap A' is provided with a plurality of button holes 50 "k" to register therewith. This said front flap A' has in connection therewith a tongue portion "m", which is provided with a button hole or other means adapted to engage with a button or like fastening means "n" 55 secured to the heel portion of the said flap A³. The sole of the boot or shoe will be joined in the usual well known manner to the foregoing described upper, and be united therewith on the bottom line extending from "g" to "h"; said two points meeting as shown in Fig. 1.

The form shown in Fig. 1 of the drawing consists of the usual construction of a shoe, but by simply adding to the stock in the 65 upper portion of the blank, and sewing at the points where buttons are shown, a boot construction may be provided.

Realizing that certain changes can be made in the form of blank shown I do not 70 limit myself to the exact configuration as illustrated in Fig. 2, and reserve the privilege of making modifications therein without departing from the original idea involved. 75

What I claim and desire to have protected by Letters Patent, is:—

In a blank for the formation of boots or shoes consisting of a single piece of material involving four distinct co-acting members 80 A, A', A², and A³, the heel portion A³ being detached from the upper A by means of an approximately right angled slit ending at "a" forming the flap "j" as an integral part of the upper A, and providing a bending line a—b; a continuous slit d to g forming the toe piece A² and securing front flap A' involving a fastening tongue member "m": substantially as described and shown. 85

In testimony whereof I affix my signature 90 in presence of two witnesses.

DOMENICK ^{his} SACK.
